(57) **CLAIM**

The ornamental design for a wheel spokes, as shown and described.

DESCRIPTION

The device is wheel for a motorcycle.

FIG. 1 is a front view of a motorcycle wheel showing the wheel spokes of my design, the reverse side being identical. FIG. 2 is a side view of the motorcycle wheel of FIG. 1; and, FIG. 3 is a perspective view of the motorcycle wheel of FIG. 1.

The broken line showing of environment is for illustrative purposes only and forms no part of the claimed design.
